PAVEMENT INSERT

Clarence C. De Lack, Albany, N.Y., assignor to Manor Crafts, Albany, N.Y., a partnership

Application July 30, 1959, Serial No. 56,996

Term of patent 14 years

(Cl. D18—2)

Fig. 1 is a plan view of a pavement insert embodying my new design; and

Fig. 2 is a sectional view thereof taken along the lines 2—2 of Fig. 1.

I claim:

The ornamental design for a pavement insert, as shown.
